UNITED STATES PATENT OFFICE

171,295

TYPEWRITER TABLE

Arthur W. Carlson, Muskegon, Mich., assignor to
E. H. Sheldon & Co., Muskegon, Mich., a corporation of Michigan

Application July 7, 1953, Serial No. 25,819

Term of patent 14 years

(Cl. D33—14)

To all whom it may concern:

Be it known that I, Arthur W. Carlson, a citizen of the United States, residing at Muskegon, in the county of Muskegon and State of Michigan, have invented a new, original, and ornamental Design for a Typewriter Table, of which the following is a specification, reference being had to the accompanying drawing forming part thereof.

Fig. 1 is a perspective view of a typewriter table, showing my new design; and

Fig. 2 is a rear elevational view thereof.

I claim:

The ornamental design for a typewriter table, substantially as shown.

ARTHUR W. CARLSON.
